UNITED STATES PATENT OFFICE.

ARTHUR P. SANBORN AND ROY C. WILSON, OF OSSINING, NEW YORK, ASSIGNEES OF ONE-THIRD TO HORACE R. HORTON, OF HAYMOUNT, BRIARCLIFF MANOR, NEW YORK.

AUTOMATIC TRAIN-STOP.

1,205,794.

Specification of Letters Patent. Patented Nov. 21, 1916.

Original application filed June 22, 1914, Serial No. 846,585. Divided and this application filed July 22, 1915. Serial No. 41,383.

To all whom it may concern:

Be it known that we, ARTHUR P. SANBORN and ROY C. WILSON, citizens of the United States, residing at Ossining, in the county of Westchester and State of New York, have invented certain new and useful Improvements in Automatic Train-Stops; and we do declare the following to be a full, clear, and exact description of the invention, such as will enable others skilled in the art to which it appertains to make and use the same.

This invention generically relates to block signaling systems but more particularly to the mechanism disposed within the engine cab for arresting the travel of the locomotive or train as the case may be.

One object of this invention is to provide a simple and efficient mechanism situated within the engine cab which, when actuated, will operate the air valve and simultaneously record the time of such operation.

A still further object resides in providing a solenoid having means at the opposite extremities thereof for coöperation with an air valve and chronometer respectively.

Another and still further object is to provide a device of the character specified which is simple, readily installed, and thoroughly dependable.

With these and other objects in view our invention consists of certain novel details of construction, and combination and arrangement of parts to be hereinafter more particularly set forth and claimed.

In the accompanying drawings in which corresponding parts are indicated by similar reference characters: Figure 1 is a longitudinal vertical section of our solenoid casing having in connection therewith a diagrammatic showing of the circuits involved in our improved train stopping mechanism; Fig. 2 is a transverse vertical section taken along the plane 2—2 of Fig. 1; Fig. 3 is a similar view taken on the line 3—3 of Fig. 1; Fig. 4 is a horizontal section taken on the line 4—4 of Fig. 1; Fig. 5 is a fragmentary view showing the switch housing, the movable arm carried thereby, and the disposition of the latter with respect to the track magnets; Fig. 6 is a fragmentary showing of a locomotive pilot beam having our improved switch housing depending therefrom and showing the disposition of the movable arm with respect to the track magnets. Fig. 7 is a top plan view partially in section of a modified form of our improved train controlling and recording mechanism, having in connection therewith a diagrammatic showing of the means for energizing the motor and magnet, the latter being shown in inoperative position; Fig. 8 is a similar view, the magnet used being shown in an operative position.

In its present illustrated embodiment our invention, which is a division of our pending application Serial No. 846,585, filed June 22, 1914, embodies a substantially rectangular casing 1 which may be located within the engine cab at any convenient point but preferably in proximity to the main air valve. This frame is provided with two doors 2 and 3 together with air pipe openings 4 which are formed therein at planes at right angles to each other to provide passages for the auxiliary air pipes 5 and 6 extending from the main air pipes of the train. A valve housing 7 provided with a rotary valve is disposed within said casing 1 at the juncture of the two pipes 5 and 6, to connect the same, said rotary valve being formed with a horizontal longitudinally projecting stem 8 carrying an upright arm 9. This latter arm, at a point suitably spaced from its free extremity, is provided with a horizontal arm or extension 10 which is likewise provided with an upright arm 10' at its free end. A coiled spring 11 situated upon the extension 9 normally holds the valve closed and arm 9' in a position substantially at right angles to the air pipe 6. The upper extremities of both arms 9 and 10' are reduced for a purpose to be hereinafter set forth. A solenoid 12 is suitably housed and supported within the upper portion of the casing 1, the central portion of said solenoid being substantially in alinement with the reduced end of the arm 10'. The core 13 of the solenoid 12 which is fixed relative to the same, has a longitudinally extending recess 14, the outer end of which communicates with a contiguously formed opening in the sole-

noid casing, while the inner end thereof opens into a channel 15, said channel forming a reduced continuation of the recess 14. arranged in the recess 14 is a plunger 16 having at its extremities two extensions 17 and 18. The extension 18 extends through the channel 15 and, if the plunger 14 has been brought to its actuated position, will project through an opening 19 formed in the 5 back of the solenoid casing and in alignment with the channel 15 of the solenoid, and extend to a point slightly to the rear thereof. If, however, the plunger is in its normal position the free end of the extension 18 will be disposed very nearly flush with the back of the solenoid 12. The remaining extension 17 of the plunger 16 projects through the opening formed in the front of the solenoid casing and has its outer portion slotted as 10 shown in Fig. 4, and connected to the arm 10'. The recess 14 is of such a length that when the plunger 16 is brought to actuated position, the arm 10' will be operated and the air valve completely opened. As this solenoid 15 completely opens the air valve and thus brings the train to an immediate stop it will, for the sake of convenience, herein-after be referred to as an emergency magnet.

30 Within the casing 1, abutting the rear of the solenoid 12 is an angular casing 21 provided with a downwardly swinging hinged cover 22 which may be fastened by any suitable locking means so as to prevent tampering with the contents of the casing. A spring motor 23 mounted within the casing 21 through a train of meshing pinions 24 rotates a removably mounted shaft 25. Carried by the shaft 25 is a metallic disk 26 35 which bears against a step 27. A clock chart 28 is disposed upon the shaft adjacent the disk 26, said chart having therein twenty-four equal divisions which correspond to the twenty-four hours of the day.

40 These twenty-four divisions may be further divided into halfhours or quarter, etc., as will be readily understood without further description. In the back of the casing 21 registering with the channel 15 in the solenoid 4 is an opening 19 which is surrounded with an inwardly projecting spider 30. Slidably supported by the spider 30 is a punch 31, the outer extremity of which is pronged. The punch 31 also carries a coiled 45 spring 32 so that after actuation it may be returned to normal position. The L-shaped bar 33 depending from the top of the casing 21 is formed with an opening in its free end which co-acts with the punch 33, forming an anvil for the latter. As the outer portion of the chart 28 rotates intermediate the pointed end of the punch 31 and anvil 33 it will be obvious that if the punch is forced inwardly it will pass through the 50 chart and into the opening and anvil 33,

thus indicating the time of the day at which the plunger 16 of the solenoid 12 was actuated and the air valve opened.

Supported in front of the chart 28 is an ink or pencil marker 34, which normally bears 70 against the face of the chart so that when the same has completed a revolution there will be an unbroken circuit thereon. This marker 34 is supported in proper position by a spring holder 35 which is secured at 75 one extremity to the door 22 as at 36. The upper end of the holder 35 is engaged with the lower extremity of a holder actuating rod 37 slidably mounted in guides 38. The free end of this rod projects through the 80 spider 30 and into the path of the extension 18 of the plunger 16, so that when the latter is actuated the holder actuating rod will also be operated and thus remove the marker from the face of the chart whenever the 85 solenoid is energized. Hence each and every actuation of the plunger will cause a break in the circuit, and inform the train despatcher the exact number of times the 90 engineer permitted his train to pass a danger signal. Moreover, as the marker holder is mounted upon the door 22, any attempt on the part of the engineer to tamper with the mechanism inclosed in the casing 22 will be noticed, inasmuch as it will remove the 95 marker from the face of the chart and break the circuit. To lock the plunger in its actuated position, there is provided a spring actuated catch 39 which engages a shoulder 40 formed on the plunger extension 17. A 100 hand release 41 enables the engineer to disengage the keeper 39 whenever desirable.

From the above it will be seen that whenever the emergency magnet or solenoid 12 is energized, the plunger 16 will be actuated, the air valve opened to apply the brakes, and the time of such application indicated on the chronometer chart. Within the casing 1 adjacent the solenoid 12 is another solenoid 42, the structure of which is 110 identical with that of the solenoid 12 with the exception that the plunger 43 mounted in the recess 44 formed in the core of the solenoid, has but one extension 45. This extension 45 has formed therein a slot 46 115 which receives the reduced end of the arm 9 hereinbefore referred to. The recess 44 is of less length than the recess 14, thus making the length of movement of the plunger 43 shorter than that of the plunger 16, and such that when said plunger 43 is actuated, the valve 7 will be only partially 120 opened, thereby bringing the train to a gradual stop. This last referred to solenoid 125 will be referred to hereinafter, for the sake of convenience, as the service air magnet because it does not completely open the air valve but simply brings the train to a gradual stop in the same manner as if the engineer had stopped the train in the ordinary 130

way. A switch panel 47 vertically supported within the casing 1 upon suitable brackets 48, carries two switches 49 and 50, and a terminal 51 for a purpose to be hereinafter referred to.

5 A battery 52 arranged within the cab at any convenient location, but preferably under the engineer's seat, supplies the necessary electrical energy for the emergency and 10 service solenoids 12 and 42 respectively, as well as for the signal lamp 53 which is also mounted within the cab at a point most likely to attract the engineer's attention.

15 Depending from the pilot beam of the engine is a hollow metal standard 54, and bolted to the lower extremity of the latter is an angular metallic housing 55 having an opening 56 formed in one side thereof. A right angularly shaped steel arm 58 having 20 an enlargement at one extremity is pivoted at its inner end within the casing 55 and projects through the opening 56 in the latter, and extends in a plane at right angles to the projecting portion sufficiently to pass 25 above and below the service and emergency magnets hereinafter to be referred to. Adjacent the inner pivoted end of the arm 58 is an upwardly and right angularly projecting branch 59, in the top of which is disposed a T-head 60. Two pairs of resilient contacts 61 and 62 are mounted within the casing 55 in coöperative relation with 30 respect to the T-head 60 so that when the arm is actuated in one direction, one pair of the members of said contacts will be brought into engagement and when said arm is operated in the opposite direction the members of the other pair of said resilient contacts will be brought into engagement as 35 will be readily understood without further description. Two equalizing coil springs 63 fasten to the casing and to opposite sides of the branch 59 of the movable arm 58 and normally maintain the latter in a horizontal position.

40 To energize the emergency and service solenoids, the latter are placed in circuit with battery 52 through the instrumentalities of the resilient contacts 61 and 62 as follows: If the movable arm 58 is actuated downwardly the resilient contacts 61 will be brought into engagement with each other so that current will flow from the positive pole of battery 52 through conductor 65, resilient 45 contacts 61, conductor 66, to the terminal 51 on the panel within the casing 1, from whence it will pass through conductor 67 to one terminal of the emergency solenoid 12, through said solenoid and conductor 67 to one terminal of the switch 50 and thence 55 through conductor 68 to the negative pole of battery 52. This circuit energizes the emergency solenoid, actuates the plunger of the latter, operates the air valve and simultaneously records the time at which said opera-

tion occurs. If, on the other hand, the movable arm 58 is moved upwardly, the resilient contacts 62 will be brought into engagement and the circuit will then be completed from the positive pole of battery 52 through 70 conductors 69 and 70, resilient contacts 62, conductor 71, electromagnet 72, the purpose of which will be hereinafter set forth, conductor 73, lamp 53, conductor 74, to one terminal of a switch 75. From the other 75 terminal of which switch it passes through a conductor 76 to one terminal of the service solenoid 42. From solenoid 42 it passes through conductor 78 to the negative pole of 80 battery 52. A metallic keeper 79 is yieldably mounted within the casing immediately above the electromagnet 72, and as the latter is energized, is attracted thereby and brought into engagement with the previously engaged resilient contacts 62 so as to 85 lock the same in adjusted position. As soon, however, as the magnet 72 is deenergized this keeper will return to its normal position and release said resilient contacts as will be 90 readily understood without further description.

To permit the engineer to occasionally test the emergency magnet, there is provided an auxiliary circuit for said emergency solenoid as follows: from the positive 95 pole of battery 52 through conductors 69 and 80 to one terminal of the switch 49 on the panel 47, the other terminal of this switch is connected by a conductor 81 to the terminal 51. From this arrangement, it will 100 be apparent that when the circuit 49 is closed a circuit will be compelled through the emergency solenoid so as to actuate the latter. For the purpose of actuating the movable arm 58 carried by the locomotive, 105 there is disposed at the entrance of each block a pair of electromagnets 82 and 83 respectively. These magnets are arranged in alignment and in planes vertically spaced so that the arm 58 will pass above one of the magnets and under the other. Dependent on which of these magnets are energized, 110 said arm will be actuated either upwardly or downwardly as the case might be. Inasmuch as the structure and operation of these track magnets are clearly set forth in my pending application, Serial Number 846,588, filed June 22, 1914, it is thought to be unnecessary to say anything further in connection with the same.

115 From the foregoing it will be obvious that if the movable arm carried by the locomotive is actuated to close the circuit of the emergency air magnet, then the air valve will be completely opened and the train or 120 locomotive brought to an emergency stop, while at the same instant, the time in which the signal was given is duly recorded. If, however, the movable arm 58 is actuated so as to close the circuit of the service solenoid, 130

then the latter will be actuated to partially open the valve and bring the train or locomotive to an ordinary stop as will be readily understood without further description.

5 As a modification we may substitute for the two solenoids 12 and 42 respectively disposed within the casing 1, a casing 1^a which is suitably formed so as to give ready access to its interior and mounted like the emergency solenoid 12 immediately to the rear of the casing 21. This casing 1^a has formed in each end thereof a bearing opening 2^a, said openings being in alinement and registering with that in casing 21 for a purpose hereinafter to be set forth. Extending longitudinally of the casing 1^a with its extremities loosely mounted in the bearing openings 2^a is a shaft 3^a. One extremity of the shaft 3^a is extended as at 4^a and provided with an opening 5^a to receive the reduced end of an arm 10', which is affixed to the extension of the air valve. The other extremity of the shaft 3^a is adapted to protrude slightly beyond the end of the casing 1^a for a purpose hereinafter to be referred to.

Laterally extending arms 7^a are integrally formed on the shaft 3^a adjacent one end of the casing and serve as an armature for a permanent magnet hereinafter to be referred to. Also on the shaft 3^a in spaced relation to the arms 7^a, which for the sake of convenience will hereinafter be referred to as an armature, there is formed a stop 8^a to limit the movement of a disk 9^a loosely mounted on the shaft intermediate the armature and stop for a purpose hereinafter to appear. Within the casing on opposite sides of the shaft 3^a are standards 10^a. Swivelly supported upon the upper extremities of the aforesaid standards is a U-shaped permanent magnet 11^a the extremities of which are enlarged as at 12^a for a purpose hereinafter to be referred to. This permanent magnet is disposed immediately above the shaft 3^a and is formed with two supporting trunnions 13^a and 13^b. Affixed to the supporting trunnion 13^a is a quadrant gear 14^a which meshes with a pinion 15^a keyed to the shaft of a suitably supported motor 16^a. The other trunnion 13^b has thereto two metallic disks 17^a. Each of the disks 17^a has on the periphery thereof a strip 17^b of insulating material, the purpose of which will appear later. A terminal block 18^a situated adjacent the disks 17^a carries two resilient fingers 19^a. The fingers 19^a have one of their extremities frictionally engaging the disks 17^a and their other extremities in contact with the terminals 20^a. A coil 21^a encompasses the intermediate portion of the U-shaped terminal magnet 10^a and has its extremities in engagement with the disks 17^a.

65 As in the modification under consideration,

the service position of the air brake is eliminated, it becomes apparent that the casing 55 depending from the pilot beam of the locomotive requires but one pair of resilient contacts 22^a which are normally held in contact by the T-head 60 of the arm 58 when the latter is in horizontal position, so that when said arm is moved downwardly the resilient fingers 22^a will be disengaged to break the circuit of the battery 23^a in a manner hereinafter to be set forth. To normally energize the motor 16^a one terminal of the latter is connected by a conductor 24^a to one of the resilient contacts 22^a, the companion contact being connected by a conductor 25^a to the negative pole of battery 23^a while the positive pole of this battery is connected by a conductor 26^a to the other terminal of the motor 16^a. From the circuit arrangement set forth it will be at once obvious that when the contacts 22^a are in engagement, the motor 16^a will be energized, its shaft rotated, and the magnet 11^a actuated until the legs thereof are disposed in a vertical plane. When in this position, which is its normal one, the magnet 11^a is inoperative. When, however, the arm 58 has been actuated so as to release the contacts 22^a, the circuit of the motor will be broken, thus allowing the legs of the magnet 11^a to drop by gravity to a horizontal plane. When the magnet is in this position, owing to the fact that the resilient fingers 19^a are now in engagement with the metallic disks 17^a, a circuit will be completed from the positive pole of battery 23^a through conductors 26^a and 27^a, one of the resilient fingers 19^a, through the coil 21^a on the permanent magnet 11^a, thence through the other finger 19^a and through the conductor 28^a to the negative pole of battery 23^a, so that when in this latter position the magnetic strength of the permanent magnet 11^a will be materially increased. As the legs of the permanent magnet 11^a attain a horizontal position, the disk 9^a on the shaft 3^a will be attracted thereby, and coming into engagement with the stop 8^a will impart movement to the shaft 3^a, gradually actuating the same horizontally through its bearings until the armature 7^a has been drawn into the full magnetic field of the magnet, which in the meantime has been materially strengthened by reason of the establishment of the circuit hereinbefore described. Therefore, since the shaft 3^a is connected to the air valve and inasmuch as said shaft is at first slowly actuated, the valve will be opened in a manner to gradually apply the air but, however, when the armature 7^a is brought into the strong magnetic field of the magnet 11^a it will be rapidly brought into engagement with the enlarged extremities of said magnet so as to quickly actuate the shaft 3^a, thus quickly completing the opening of the air valve as

will be readily understood without further description. Moreover, since the extremity of the shaft 3^a is disposed in alinement with the opening 19 in the casing 21, as said shaft 5 is moved horizontally it will coöperate with the recording mechanism in a manner similar to the extension on the plunger 16 of the emergency magnet hereinbefore referred to. When the permanent magnet 11^a has its legs 10 disposed in a vertical plane, or in other words is in inoperative position, the insulating material 17^b on the disks 17^a will be in engagement with the fingers 19^a so as to break the battery circuit through the coil 21^a; hence when the magnet is in an inoperative position its magnetic strength will be greatly decreased as will be understood without further description. Also from the foregoing it will be seen that we have provided a block signaling system which is simple, efficient, and one which will not only warn the engineer as well as stop his train, but will also record each danger signal which he fails to heed.

25 Although we have described certain elements as best adapted to perform the functions allotted to them, nevertheless it is to be understood that various minor changes as to form, substance, etc., may be resorted to 30 within the scope of the appended claim without departing from or sacrificing any of the principles of this invention.

We claim as our invention:—

In a device of the character described, the combination with a rotary air controlling valve having a stem projecting longitudinally therefrom, and a pair of arms carried by said stem; of a service and an emergency solenoid having relatively fixed cores therein, said cores being provided with recesses in their ends adjacent said arms and extending longitudinally of the former, the recess in the core of said emergency solenoid being greater in length than the recess in the core of said service solenoid, reciprocating 40 plungers slidably mounted in said recesses and having slots in their outer ends, said arms extending through said slots to provide an operative connection between the former and said plungers, the slot in the 45 plunger of said emergency solenoid being greater in length than the slot in the plunger of said service solenoid, whereby said valve is operated independently by either of 50 said solenoids, and means for energizing the 55 latter.

In testimony whereof we have hereunto set our hands in presence of two subscribing witnesses.

ARTHUR P. SANBORN.
ROY C. WILSON.
